(57) **CLAIM**

The ornamental design for a printer, as shown and described.

DESCRIPTION

FIG. 1 is a front perspective view of the first and second embodiments of the printer embodying our new design;

FIG. 2 is a top plan view thereof;

FIG. 3 is a bottom plan view thereof;

FIG. 4 is a left side view thereof;

FIG. 5 is a right side view thereof;

FIG. 6 is a front view thereof;

FIG. 7 is a rear view thereof; and,

FIG. 8 is a rear perspective view of a second embodiment of the printer embodying our new design showing a clip on the rear of the printer which otherwise is the same as the first embodiment, the front perspective view of FIG. 1 and the front view of FIG. 6 being identical to the first embodiment.

1 Claim, 5 Drawing Sheets
